(No Model.)

F. KEEFER,

SECTIONAL BLOCK FOR STEREO TYPE PLATES.

No. 268,688.

Patented Dec. 5, 1882.

UNITED STATES PATENT OFFICE.

FRANK KEEFER, OF CHICAGO, ILLINOIS.

SECTIONAL BLOCK FOR STEREOTYPE-PLATES.

SPECIFICATION forming part of Letters Patent No. 268,688, dated December 5, 1882.

Application filed August 31, 1881. (No model.)

To all whom it may concern:

Be it known that I, FRANK KEEFER, a citizen of the United States, residing in Chicago, in the county of Cook and State of Illinois, have 5 invented a certain new and useful Sectional Block for Stereotype-Plates, of which the following is a specification.

My invention relates to improvements in sectional blocks in which any number of a 10 series of sections may be arranged contiguous to each other to form blocks for supporting varying sizes of stereotype-plates, the sections at the four corners of such blocks being provided with clamping mechanism for holding 15 the plate.

The object of my invention is to furnish a sectional block composed of five sections—namely, one center and four corner sections, said corner sections being rectangular in shape 20 and fitting into corresponding recesses in the corners of the center section, the whole of which is adapted to mount any sized plate, either by adjusting the clamping devices embedded in the corner sections or by changing 25 the center section. I attain these objects by devices illustrated in the accompanying drawings, in which—

Figure 1 is a perspective of a sectional block embodying my invention; Fig. 2, a plan view, 30 of one of the ratchet-lugs detached from its guide; Fig. 3, a cross-section through one of the sections and clamping device, and Fig. 4 a perspective of one of the extension-plates.

A B C D represent four rectangular-shaped 35 blocks having the required thickness for and forming the four corner pieces of my sectional block.

E represents the main body of my block, consisting of a single piece, cross or X shape 40 in form, the angles of which correspond with and are adapted to receive the corner blocks A B C D. The block E corresponds in outer dimensions with the size of the required plate to be supported, and its angles, receiving the 45 corner blocks, correspond with such blocks without regard to the dimensions of the block E.

It will readily be understood that, when having a set of the corner blocks, any size of block required for a particular stereotype-plate 50 may be quickly and readily made by taking a solid block of corresponding size, and recessing such block to receive the corner sections.

In view of the fact that devices are required for clamping the plate to the supporting-block, and that such devices may be permanently secured to the corner blocks, it will be understood that when having the corner blocks at hand a block may be formed of the required size for the particular plate to be used by taking a solid block of the size of the plates 55 and recessing its corners to correspond with and receive the corner sections carrying the clamping mechanism, thus obviating the necessity of alterations in but one of the series of sections forming the sectional block, and the perplexity heretofore experienced in assorting 60 and fitting a number of sections to the desired sized block.

In sectional blocks heretofore referred to, where more than four sections are used, each 70 section is subject to a side and end pressure from at least two sections of the same series, so that when being locked in the chase, if the pressure of the furniture is greater on one side than on the other, there is danger of its losing 75 its rectilineal shape. My invention avoids this difficulty by having the four corner sections bear against the solid sides of the rectangular recesses in the corners of the center section. This cross-shaped block or section indicates 80 of itself the size of block which it will form, and may be marked accordingly, or the plate placed upon it so as to be readily and quickly selected and the corner sections attached, thus saving no inconsiderable amount of time and 85 labor in mounting plates.

Corner section A is recessed to receive a countersunk plate having upon one side a ratchet-bar, a, and provided with flanges forming guides for a ratchet-lug, a', beveled upon 90 one edge, leaving a space between it and the countersunk plate for a wedge-key, a², which, when inserted, serves to lock the ratchet-lug with the ratchet-teeth of the plate. This ratchet-lug is provided with a stud, 1, adapted to engage with the edge of the plate, the whole forming a clamping or tightening device for holding 95 the stereotype-plate on the block.

Section B is provided with two similar clamping devices arranged at right angles to each 100 other, and adapted to embrace one corner of the plate, while section D is provided with but one such device.

Sections A C are recessed upon one edge to

receive plates 2 3, the projecting lugs 4 5 of which respectively are beveled to correspond with the beveled edge of the stereotype-plate which they hold, and project over the edge of 5 the block, so as to prevent the furniture between the blocks from rising.

Sections C D are provided with lug-plates 6 7, respectively, similar in construction, except that the inner faces of the lug are vertical, to 10 correspond with the opposing edge of the stereotype-plate, which always has one vertical edge, and are perforated to receive corresponding pins upon small metal plates b b, designed to be interposed between the lugs and the edge 15 of an electroplate having somewhat less length than the block, which may have been made for a slightly longer plate, thus accommodating the block to plates at slight variance in length.

Lugs 6 7 may of course be substituted for 20 lugs 4 5, if deemed necessary; but usually electroplates approximating a given or standard size will vary in length, but not in width.

Sections B D are also provided upon their 25 outer edges with countersunk L-plates 6 7, the upper ends of which are in plane with the face of the sections, but project sufficiently to hold down the furniture in the same manner as the lug-plates above described.

After putting the sections of the blocks together and securing it in a chase, and then placing the plate upon the block with one side and end edge abutting against lugs 4 5 6 7, it will be seen that by tightening the ratchet-lugs and securing them in place by inserting 35 the wedge-keys the plate will be held firmly.

Having thus described my invention, what

I claim, and desire to secure by Letters Patent, is—

1. In a sectional block for stereotype-plates, the combination, with the block having its 40 four corners cut away to form recesses, and having four outward bearing surfaces, of a series of removable sections carrying suitable clamping mechanism and filling said recesses, substantially as and for the purpose set forth. 45

2. In a sectional block, a cross or X shaped block, in combination with sections fitting in the angles of said cross to form a rectangular block, substantially as described and shown.

3. A stereotype-plate block provided with a 50 tightening device consisting of a recessed plate having a ratchet-bar, a lug engaging with said bar, a stud upon said lug adapted to engage with the plate, and a wedge-key, substantially as described and shown.

4. The stereotype-plate block having attached to its outer edges one or more stud-plates adapted to support the edges of the plate, and provided with projections extending outside of the edge of the block, for preventing the furniture, &c., from rising, as described and shown. 55

5. The combination, with the block having studs supporting the edges of the plate, and perforated as described, of extension-plates 60 entering said perforations, substantially as described and shown. 65

FRANK KEEFER.
